MACHINE FOR RECIPROCATING A TOOL

John W. Reed, Little Falls, N. J.

Application April 26, 1940, Serial No. 331,882

2 Claims. (Cl. 74—37)

This invention aims to provide a simple but effective power-driven means for imparting reciprocation to a hack saw, file, sand block, or the like.

5 It is within the province of the disclosure to improve generally and to enhance the utility of devices of that type to which the present invention appertains.

With the above and other objects in view, 10 which will appear as the description proceeds, the invention resides in the combination and arrangement of parts and in the details of construction hereinafter described and claimed, it being understood that changes in the precise 15 embodiment of the invention herein disclosed, may be made within the scope of what is claimed, without departing from the spirit of the invention.

In the accompanying drawings:

20 Fig. 1 shows, in side elevation, a device constructed in accordance with the invention;

Fig. 2 is a horizontal section taken approximately on the line 2—2 of Fig. 1;

Fig. 3 is a section on the line 3—3 of Fig. 2;

25 Figs. 4, 5 and 6 are sections taken, respectively, on the lines 4—4, 5—5 and 6—6 of Fig. 3;

Figs. 7 and 8 are diagrams illustrating the operation of the tool carrier.

In carrying out the invention, there is provided an elongated box-like casing C, including 30 a body 1 having a longitudinal midrib 2, extended inwardly from one side of the body. The opposite side of the body 1 is closed by a cover 3, attached by securing elements 4 to the mid-rib 2, and by securing elements 5 to the body 1.

Vertical holders 6 are located near the ends 35 of the casing C and have vertically elongated recesses 7 that face the cover 3, the holders being held in place by certain of the securing elements 5. A loop-shaped guide slot 8 is formed in the cover 3, and extends lengthwise of the casing C.

A power-driven shaft 9 is disposed longitudinally of the casing C and is journaled for rotation in the body 1, at one side thereof. The shaft 9 carries a worm 10, meshing with a worm wheel 11, mounted to turn on a stub shaft 12 carried by the side portion of the body 1. A driving sprocket wheel 14 is journaled on the 40 stub shaft 12 and is connected with the worm wheel 11, to turn therewith.

An idle sprocket wheel 15 is located at the end 45 of the body 1 which is remote from the driving sprocket wheel 14, the sprocket wheel 15 being journaled on a stub shaft 16, mounted in the

side of the body 1. The sprocket wheels 14 and 15 are operatively connected by a sprocket chain 17.

A tool carrier 18, in the form of a bar, extends lengthwise of the casing C and is received in the recesses 7 of the holders 6. The tool carrier 18 has two movements. One of these movements is a longitudinal movement, and the other is a transverse movement parallel to the driving sprocket wheel 14, an observation which will be 10 understood readily when Fig. 4 is noted. The tool carrier 18 is shown as provided with rectangularly disposed arms 19, carrying a hack saw 20, but the tool to be reciprocated is a matter of choice. The machine will operate a sand 15 block (not shown), a file (not shown), or any analogous tool.

A bracket 21 is secured to the sprocket chain 17 and has a lateral foot 22, receiving a ball 23 on the inner end of a securing element 24, 20 mounted in the tool carrier 18. The securing element 24 is adapted to move in the loop-shaped slot 8 of the cover 3.

On its inner side, the tool carrier 18 is provided with a loop-shaped groove or guide 25. 25 The cover 3 carries an outwardly extended projection 26, received in the loop-shaped groove 25 of the tool carrier 18. The projection 26 is coaxial with respect to the stub shaft 12 of Fig. 3, and is indicated in that figure by a dotted line. 30

The driving train for the tool carrier 18 includes the power shaft 9, the worm 10, the worm wheel 11, the driving sprocket 14, and the chain 17. The bracket 21 on the sprocket chain, the foot 22 and the ball 23 cause the securing element 24 to move in an orbit, that orbit being determined, since the securing element 24 traverses the loop-shaped slot 8 of the part 3 of the casing C. Since the securing element 24 is mounted in the tool carrier 18, the tool carrier 35 advances with the hack saw 20 in contact with the work, the tool carrier being elevated at the forward end of the working stroke, and being carried backwardly, since the securing element 40 24 moves in the loop-shaped slot 8 of the casing part 3.

The fixed projection 26 cooperates with the loop-shaped groove 25 of the tool carrier 18, to maintain the tool carrier in proper working position, an observation which will be understood clearly when Figs. 7 and 8 of the drawings are noted. 50

The device is of simple construction but will 55 be found thoroughly effective to consummate the

object set forth in the opening portion of this specification.

Having thus described the invention, what is claimed is:

- 5 1. A machine for reciprocating a tool, illustratively represented by a hack saw, comprising a support having an elongated loop-shaped guide, a tool carrier having an elongated loop-shaped guide, a projection on the carrier and received in the guide of the support, a fixed projection on the casing and received in the guide of the tool carrier, and means on the support for moving the projection of the carrier in an orbit determined by the guide of the support.
- 10 10 received in the guide of the support, a fixed projection on the casing and received in the guide of the tool carrier, and means on the support for moving the projection of the carrier in an orbit determined by the guide of the support.
- 15 15 2. A machine for reciprocating a tool, illus-

tratively represented by a hack saw, comprising a support having an elongated loop-shaped guide, a tool carrier having an elongated loop-shaped guide, a projection on the carrier and received in the guide of the support, a fixed projection on the casing and received in the guide of the tool carrier, a sprocket chain mounted to move on the support, and a connection between the sprocket chain and the projection of the carrier, the sprocket chain and the connection constituting means for moving the projection of the carrier in an orbit determined by the guide of the support.

JOHN W. REED. 15
